UNITED STATES PATENT OFFICE.

CHARLES K. MARSHALL, OF VICKSBURG, ASSIGNOR OF ONE-HALF TO
WILLIAM LEWIS NUGENT, OF JACKSON, MISSISSIPPI.

MACHINE FOR DELINTING COTTON-SEED.

SPECIFICATION forming part of Letters Patent No. 431,665, dated July 8, 1890.

Application filed October 2, 1889. Serial No. 325,800. (No model.)

To all whom it may concern:

Be it known that I, CHARLES K. MARSHALL, a citizen of the United States, residing at Vicksburg, in the county of Warren and State 5 of Mississippi, have invented certain new and useful Improvements in Machines for Delinting Cotton-Seed; and I do hereby declare the following to be a full, clear, and exact description of the invention, such as will enable 10 others skilled in the art to which it appertains to make and use the same.

My invention consists in a novel combination of parts whereby cotton-seeds are passed from one hopper, then blown by a fan beneath 15 a curved director into another hopper, and from said hopper are lifted by an endless carrier and delivered between scouring-surfaces of a cotton-delinting machine, the combination being such that the seeds are spread out 20 in a broad thin sheet and deprived of dirt and other foreign substances between the first and second hoppers, and are thus put in a condition for being rapidly and constantly fed by the endless carrier to a cotton-delinting 25 machine having a shallow yet very long feed-passage without liability of the machine clogging.

My invention also consists in the combination of an endless scouring-belt, an inclined 30 screen, and a rotary finisher or polisher consisting of a stationary disk having scouring-surfaces and a revolving disk having a feeding-eye and dressed with brushes or other 35 analogous scouring projections, whereby the seeds are first deprived of adhering cotton-lint and then further rubbed for the purpose of removing all the fine cotton fuzz and finishing them with a clean or polished surface.

My invention also consists in certain other 40 combinations, as will be hereinafter described and claimed.

In the accompanying drawings, Figure 1 is 45 a longitudinal section of my improved feeding mechanism in connection with a scouring-section of a cotton-delinting machine, which may be similar to one of the scouring-sections shown in an application for a patent filed by me July 3, 1889, Serial No. 316,877, the said feed mechanism and scouring-section 50 being shown in connection with rotary finishing or polishing mechanism. Fig. 2 is a plan

view of a portion of the finishing or polishing mechanism. Fig. 3 is a vertical section on an enlarged scale of the frame and of the receiving and discharging gutter of the finisher 55 or polisher and an elevation of the finisher or polishing mechanism. Fig. 4 is a broken vertical section and partial elevation of the finishing or polishing machine and its frame. Fig. 5 is a detail section of part of the upper 60 and lower finishing polishing disks. Fig. 6 is a broken detail sectional view showing in part the endless carrier, comb-plate, and delivery-hopper. Fig. 7 is a broken plan view showing the relation of the teeth of the endless 65 carrier to the comb-plate. Fig. 8 is a detail rear view of the blast-fan, showing both its tapered and flaring form. Fig. 9 is a side elevation of my invention, illustrating a mode of driving.

A in Fig. 1 is designed to represent a portion of a scouring-section similar to what is shown in my aforesaid application, the same here consisting of an endless slatted belt *a*, suitably dressed with rubbing and scouring 75 means, an inclined screen *b*, conducting tail-board *c*, a revolving cylinder *b*, with bristles or pins in its periphery at the mouth of the scouring mechanism, and frame *f* for supporting the same, said frame being inclosed by a 80 casing *f'*. I wish it to be understood that these parts may be constructed and operated and combined with an air-tight casing and suction-fan and trunk in substantially the manner and for the same purpose as in my 85 aforesaid application, and therefore a further illustration and description of the same here is unnecessary, as no claim is made in this application to said scouring-section or the parts thereof separately.

B represents a chamber, closed at front, sides, back, and top, and resting upon the ground or flooring of a building.

C is a main feed-hopper on top of the chamber at the rear end thereof, and D is another 95 hopper at the forward top end of said chamber, from which the cotton-seeds are delivered to the scouring mechanism at A by means presently described.

E is a refuse and air-escape flue leading 100 from the hopper D. Within the hopper D a toothed elevator in form of an endless belt F

is applied in an inclined position upon rollers $e' e'$, so that the belt on its rear side is parallel with and touches or nearly touches the rear inclined side of the said hopper. This 5 elevator reaches from the bottom or angle g of the hopper to a position above its upper edge, so that the seed carried up by the teeth or hooks h on the belt F are discharged upon an inclined conducting-board m , which forms 10 a part of the mouth of the scouring-section A , and are thereby placed in a position for being forced or urged between the parts of said mechanism by the revolving brush or pin cylinder d , as in my aforesaid application. 15

Behind the roller e' at the top of the belt, and also forward of the same, plates $m' m^2$ are provided, the rear one m' serving for keeping back surplus seed as the teeth go upward, 20 and the forward one m^2 , which is toothed similar to a comb, preventing seed passing back as the teeth go downward. The plate m' may be fitted as a slide and adjusted farther away from or nearer to the elevator 25 and confined by a screw m^3 , and thus regulate the amount of seed supplied to the scouring-section A .

In the main hopper C a swinging valve-plate n is applied and made adjustable by a screw 30 n' , so as to decrease or increase the size of the discharge-passage at the bottom or angle of said hopper, and a revolving spiked cylinder n^2 or other equivalent agitator may be applied in the hopper for insuring a uniform discharge 35 of the seed.

Between the hoppers C and D the metal top of the chamber B is curved, as shown at B' , and said curved portion rises higher than the rear side of the hopper D in order to leave a 40 passage G for cotton-seed into said hopper beneath the curved part of the top, as shown.

H is a blast-fan arranged in the bottom of chamber B , directly under the main hopper C . The nozzle or discharge end H' of the fan-case is made with a taper and flared laterally, so as to discharge the air in a broad thin sheet the full length of the hopper C and nearly the full width of the scouring-section A . The said nozzle extends up very near to 45 the angle or bottom of the hopper, and its discharge end is in rear of the discharge-opening of the hopper, and therefore when the blast of the fan escapes it strikes the cotton-seed falling from said opening of the hopper and 50 carries them on a curved line corresponding to the curvature of the top B' of the chamber B and forces them into the hopper D , as illustrated in the drawings, and as the seeds pass to the hopper D any sticks, stones, nails, 55 and refuse of greater specific gravity than the seed and of a weight sufficient to overcome the force of the blast are deflected by the rear inclined side of the hopper D and deposited in the chamber B , as also illustrated in the 60 drawings.

It will be understood that as my cotton-seed-

delinting machine may be from three to four feet wide, and the spaces between the scouring-surfaces shallow, it is a desideratum to have the seed supplied regularly in thin 70 masses. This is accomplished very satisfactorily by elevating or feeding the seeds, which are blown in thin masses into the hopper by the blast-fan, by the broad-toothed elevator or feed-belt F , and from thence delivering the 75 broad thin masses into the scouring-section A .

In connection with scouring mechanism, as A , I employ a finisher or polisher, consisting of a stationary frame I , a circular guttered seed-receiver i , having an inclined bottom i' 80 and a discharge-chute i^2 , a vertical shaft J , a stationary perforated screening-disk $K r$, dressed on top with a suitable frictional cleaning-surface of square woven wire j , and a revolving circular disk L , dressed on its under 85 side with tufts or bristles, forming a brushing and polishing disk. The brushing and polishing disk L works in concert with the frictional screening-surface of disk K , and the cotton-seeds, which have been almost completely deprived of lint in the section A of the machine, 90 are finished or polished.

It would be impracticable to put cotton-seeds which have not been delinted into the finisher or polisher, and it is only intended 95 to employ the finisher or polisher as an adjunct of a delinting-machine, as illustrated in the drawings.

For the purpose of rendering the brushing-disk self-adjusting and varying its force a 100 spring k is fitted around the upper end of the shaft J and made to rest on a collar l of the shaft J , and against this spring a collar k' of an adjusting-screw M is made to bear. The screw M is fitted to a standard M' of the frame 105 I , and by turning it down the pressure is increased and by turning it up it is decreased. If the disks K and L should become clogged, the spring allows the upper disk to yield, and thus avoid breakage of the machinery. Said 110 spring also insures a sufficient frictional contact of the brushes of the disk with the seeds passing between the disks. At the center of the disk L a feeding-eye P is provided, and immediately beneath this eye a series of shallow curved guiding conducting-ribs n^4 , Fig. 2, are provided upon the stationary disk K , so as to insure the flowing of the seeds beneath the disks under the action of the revolving brushing-disk. The seeds as fast as 115 finished or polished between the disks pass out at the peripheries of the disks and fall into the gutter of the receiver and chute i' , and therefrom are discharged at i^2 , which is at the lowest point of the receiver and chute, 120 as indicated by dotted lines in Fig. 3. By setting the receiver inclined the seeds will flow away continuously, but they may be raked out of the gutter by a hand implement. The seeds are delivered from the delinter-section 125 A upon the tail-board c into the eye of the finisher or polisher, as will be seen from the 130

drawings. It is contemplated to have the finished or polished seed fall through a blast, which will blow away the dust and fine lint without carrying the seed along with the same, 5 or the perforations r of the frictional cleaning and scouring disk K may be in communication with an air-trunk of a fan, which is connected with the delinting-section A, as in my aforesaid application, and this fine dust 10 and lint may be carried into the same trunk. In Fig. 9 of the drawings it will be seen that the blast-fan H is driven by a belt 1, the agitator n^2 by a belt 2, the endless feeder or elevator F by a belt 3, the endless slatted 15 scouring apron or belt a by a crossed belt 4, the shaft J of the finishing or polishing disk L by a crossed belt 5, straight belt 6, and a pulley-shaft 7, all of said belts being driven from one shaft 8, provided with suitable-sized 20 speed-pulleys. If desired, the belt 2 may be dispensed with and a different style of agitator substituted for the agitator n^2 , and of course the arrangement of the driving-gearing 25 may be changed to suit location and movements of the machine, and instead of using only one section A of scouring mechanism two or more may be employed, as in my aforesaid application.

What I claim is—

30 1. In a cotton-seed feeder for a cotton-seed-delinting machine, the combination of the chamber B, having top curved plate or board B', hoppers C and D, blast-fan H, and endless elevator-belt F, substantially as described.

2. The combination of the blast-fan H, having a tapered and flaring nozzle H', the curved top plate B' of the chamber B, and the hoppers C and D, substantially as described.

40 3. The combination of the blast-fan H, having a tapered and flaring nozzle H', the curved top plate B' of chamber B, the hoppers C and D, and the endless elevator F in the hopper D, extending up beyond the top of the said 45 hopper, and a scouring and delinting machine, substantially as described.

4. The combination of the hopper C, having a feed-regulating plate n , the hopper D, having a plate m' , for keeping back the 50 surface plus cotton-seed, and a comb-plate m^2 , for insuring the discharge of the seed into the delinting-machine, an endless toothed elevator

F, a chamber B, blast-fan H, and a cotton-delinting machine, substantially as described.

5. The combination of the blast, feeding, 55 and spreading mechanism, the endless, slatted, inclined, and vertically-revolving cotton-seed scouring and delinting mechanism, and the horizontal cotton-seed finishing or polishing mechanism, substantially as described. 60

6. The combination of the delinter mechanism comprising an endless revolving scouring-belt, a stationary inclined screen, and a tail-board, and a finishing or polishing mechanism comprising a revolving horizontal disk 65 provided with brushes, a stationary disk provided with a screen-like rubbing-surface, and an inclined stationary chamber having a discharging-chute, substantially as described.

7. The combination of the endless, slatted, 70 inclined, and vertically-revolving cotton-seed scouring and delinting mechanism with the horizontal finishing or polishing mechanism comprising a revolving horizontal disk having a central feeding-eye and dressed on its 75 under surface with brushes, and a stationary disk provided with a screen-like scouring-surface and connecting and seed-conducting means between the two mechanisms, substantially as described. 80

8. The combination of the automatic feed mechanism comprising a blast-fan having a tapered and flared nozzle, curved top plate, hoppers, endless elevator, and seed-controlling plates, with the endless, slatted, inclined, and 85 vertically-revolving scouring mechanism and a horizontal cotton-seed finishing or polishing mechanism, substantially as described.

9. The combination of the delinter mechanism comprising an endless, revolving, slatted, scouring belt or apron, a stationary inclined screen, and a tail-board, and a horizontal finishing or polishing machine comprising a revolving disk provided with 90 brushes, and a stationary disk provided with 95 a screen-like rubbing-surface, substantially as described.

In testimony whereof I hereunto affix my signature in presence of two witnesses.

CHARLES K. MARSHALL.
